UNITED STATES PATENT OFFICE.

WILLIAM F. GEORGE, OF NEW YORK, N. Y.

PANORAMIC TOY.

SPECIFICATION forming part of Letters Patent No. 247,336, dated September 20, 1881.

Application filed June 24, 1881. (No model.)

To all whom it may concern:

Be it known that I, WILLIAM F. GEORGE, of the city and county of New York, in the State of New York, have invented a certain 55 new and Improved Panoramic Toy, of which the following is a specification.

My invention consists in the combination, in a panoramic toy, with the two rollers and a picture strip or band attached at its ends to 10 said rollers, of a box or case which has an opening in its top, through which the said picture strip or band is visible, and which is divided through its sides and has bearings for said rollers in the line of division formed in the 15 meeting edges of the two parts of the box or case. The two parts of the box or case are hinged together, and when opened the rollers may be lifted out of their bearings.

The invention also consists in the combination, with the above, of friction-brakes applied 20 to the rollers for retarding their rotation and preventing the picture strip or band from becoming slack between the rollers.

The invention also consists in the combination, with the box and rollers, of a board or rest placed below the opening in the top of the box, and over which the picture strip or band is carried, whereby said strip or band is supported and the liability of its being punctured is obviated, and an elastic strip attached to said 25 board or rest and having its ends bearing upon the journals of said rollers to form brakes for retarding their motion.

In the accompanying drawings, Figure 1 35 represents a perspective view of my improved toy with the box or case open, and Fig. 2 represents a sectional view thereof.

Similar letters of reference designate corresponding parts in both figures.

40 A A designate a rectangular box or case, which may be made of wood or other material, and is composed of two parts, hinged together at a, and provided with a hook, b, or other suitable catch for retaining the two parts together.

45 B B designate two rollers, which may be of wood, and which carry a strip or band, C, of paper, cloth, or other material. The strip or band C has printed, pasted, or otherwise delineated upon it or attached to it the pictures which are to be exhibited, and I therefore term

it a picture strip or band. The said strip or band may be attached at its ends to the rollers B B in any suitable manner; but as here shown each roller has formed in it a longitudinal groove, e, into which the end portion of the picture strip or band C is pressed and secured by a strip, d, which may be tacked or otherwise secured in the groove.

B' designates the journals of the rollers, and e designates bearings therefor, which are formed partly in each part A of the box at the line of division, as clearly seen in Fig. 1. When the two parts of the box or case are held together, as in Fig. 2, the journals of the rollers are held 65 securely in their bearings; but when the box or case is opened, as in Fig. 1, the rollers may be removed from their bearings, if desirable.

In the top of the box or case is an opening, A', and D designates cross bars or rods placed 70 in proximity to the ends of said opening, and over which the picture strip or band is passed between the rollers.

The box is represented in Fig. 2 as provided in that part which contains the opening A' 75 with a board or rest, E, secured to the sides of the said part of the box immediately below said opening. The strip or band C passes over this board or rest, and hence the liability of the said strip or band being punctured by a 80 child, as it might otherwise be, is greatly lessened.

In lieu of the cross bars or rods D, the ends of the board or rest E might be rounded off where the strip or band passes over them. 85

The journals B' of the rollers B fit quite loosely in the bearings, and in order to prevent the strip or band C from becoming slack or loose between the rollers I employ friction-brakes for retarding the rotation of the rollers. 90

In Fig. 1 I have shown plugs or blocks f, of rubber, secured in the bearings for the rollers; but in lieu of these I might employ a strip, F, of wood or metal, secured at about the middle of its length to the board or rest E, and having its end portions bearing upon the journals of the rollers B, as seen in Fig. 2.

By my invention I provide a very simple and cheap toy, which will afford great amusement to children.

I am aware that toy panoramas have been made in which the panoramic strip or picture-

strip is attached at its ends to rollers which are contained within a box or case and have their journals fitting in bearings in the sides of said box or case; but I am not aware of 5 any such toy in which the box or case is divided or composed of two approximately similar parts in the meeting edges of which are formed bearings for the roller-journals; and I am not aware of any such toy in which brakes are provided for retarding the motion of the rollers. 10 By simply opening my box or case the journals of the rollers are uncovered, and the rollers, with the attached panoramic strip, can be lifted out, thus greatly facilitating the attachment 15 of a new panoramic strip. My construction also provides for using a number of panoramic strips which have a roller or rollers permanently attached to them, in which case the panoramic strip may be rolled upon one of said 20 rollers when it is removed from the box or case. I am also aware that it is old to provide a board or rest opposite the hole or opening in the box or case through which the pictures are viewed and over which the panoramic strip 25 passes, and I therefore make no claim thereto except in combination with the elastic brake-strip F.

What I claim as my invention, and desire to secure by Letters Patent, is—

1. The combination, with the picture strip 30 or band C and the rollers B, of the box or case composed of the two parts A A, having bearings for the journals of said rollers formed in their meeting edges, substantially as specified.

2. The combination of the box or case composed of the two parts A A, hinged together, the rollers B, fitting in bearings formed in the meeting edges of the parts A A, the strip or band C, attached to said rollers, and brakes applied to said rollers to retard their rotary 35 motion, substantially as specified.

3. The combination of the divided box or case A A, having an opening, A', in the top, the rollers B B, picture strip or band C, the board or rest E for the strip or band, arranged 45 opposite the said opening, and the elastic strip F, attached to said board or rest and having its end portions bearing upon the journals of said rollers to form brakes, substantially as specified.

WM. F. GEORGE.
